(57) **CLAIM**

We claim the ornamental design for an automatic urine accumulator, as shown and described.

DESCRIPTION

FIG. 1 is a front, top and right side perspective view of an automatic urine accumulator showing our new design;

FIG. 2 is a front elevational view thereof;

FIG. 3 is a right side elevational view thereof;

FIG. 4 is a left side elevational view thereof;

FIG. 5 is a top plan elevational view thereof;

FIG. 6 is a bottom plan elevational view thereof; and

FIG. 7 is a rear elevational view thereof;

FIG. 8 is a front, top and right side perspective view thereof with the covers are opened; and,

FIG. 9 is a right side elevational view thereof with the handle is raised.
